ABSTRACT OF THE DISCLOSURE

Compounds and chelates formed by the reaction of β,β -dialkylcysteines with organometallic compounds and metallic salts, wherein the metals are arsenic, antimony, bismuth and iron are described. The compounds and chelates reduce the toxicity of the metallic compounds without substantially impairing the therapeutic effectiveness of the metallic radical, thus greatly increasing the therapeutic index.

This invention relates to metal and organometallic derivatives of dialkylcysteines and allied compounds, and to their preparation.

A number of metallic radicals, for example arsenic, bismuth and antimony, impart to certain of their compounds valuable properties as therapeutic agents. Unfortunately these compounds are commonly of high toxicity, with the result that the dose which can be administered to a patient without undesirable side effects is limited: in other words, they have a low therapeutic index (i.e. Tolerated/Effective dose).

It has long been known that thiol compounds detoxify arsenicals. More recently dimercaptopropanol (BAL)

has been introduced as an effective agent against poisoning with arsenic, antimony and mercury compounds. However the use of mixtures or complexes of these thiol compounds with metal containing preparations for therapy have not hitherto been practicable, since the therapeutic activity is also inhibited and the metallic compounds are not only detoxified but also deactivated.

The action of the above mentioned compounds as agents against metal poisoning appears to be related to their activity as metal binding agents, due to the ability of the sulphur atoms they contain to form coordinate bonds with metal, particularly heavy metal, atoms, and in particular to the formation of chelates in which interaction between the metallic compound concerned and the thiol compound results in the incorporation of the metal atom into a heterocyclic ring containing at least one coordinate bond to the metal atom.

I have discovered that β,β -dialkyl cysteines of the formula

(wherein R_1 and $\text{R}_2=\text{CH}_3$ or C_2H_5), and to a lesser ex-

tent their acetyl derivatives, reduce the toxicity of metallic compounds, while not substantially impairing the therapeutic effectiveness of the metallic radical. This is particularly surprising since related thiol antidotes, such as cysteine and dimercaptosuccinate so not have the same effect.

This improved therapeutic index both increases the patient's tolerance of therapeutically effective metallic compounds, while reducing side effects, and permits a larger amount of a therapeutic preparation containing metallic compounds to be administered thereby improving its therapeutic effectiveness.

I have found that the reaction of dialkylcysteines, or analogues of dialkylcysteines in which the sulphur atom is replaced by selenium or tellurium, with metallic compounds produces compounds, complexes, or compound-complexes, generally chelates, of low toxicity, many of which possess therapeutic activity. It is well known that certain metallic radicals, such as antimony (trivalent or pentavalent) are effective antiparasitic agents. Their usefulness is however limited in that they must often be used in the form of compounds of a relatively high toxicity. I have found that dialkylcysteine derivatives containing antimony are effective antiparasitic agents of low toxicity, and it is believed that the dialkylcysteine radical increases the penetration of the metallic radical into the parasite, at the same time facilitating its elimination from the host.

Likewise, dialkylcysteine derivatives of other metals and organo metallic compounds provide a method of introducing these metals and compounds into a patient in an effective and relatively non toxic form, the dialkylcysteine radical improving the availability of the metallic radical and at the same time assisting in its elimination from the patient.

Accordingly, the invention relates to novel metal and organo metallic derivatives of dialkylcysteines and related compounds having the following general formula

or their acid salts, where y is 0 or an integer less than or equal to $v-x$ where v is the valency of the metal, z is 0 (except when y is 0) or an integer less than or equal to $w-y$, where w is the maximum number of coordinate bonds which can be formed with the metal, x is 0 or an integer up to v , Me is antimony (trivalent or pentavalent), arsenic, bismuth, iron (divalent or trivalent), selenium, or tellurium, or mercury, A is an organic or inorganic radical or radicals or where x is two or more, the remainder of a heterocyclic ring in which Me is included, R_1 and R_2 are $-\text{CH}_3$ or $-\text{C}_2\text{H}_5$ and R_3 is $-\text{H}$ or $-\text{CO.CH}_3$.

The invention extends to a method of preparing the above derivatives by reacting a metallic or organo metallic compound of the formula $\text{A}_x\text{Me.B}_u$, where B is an inorganic radical or radicals and u is $x-v$, or when $x=v$, 0, with a dialkylcysteine or analogue thereof of the formula

or hydrohalide thereof.

The invention also extends to pharmaceutical products including one or more of the above derivatives or capable of forming such derivatives in solution. The reaction between the metallic starting compound and the dialkylcysteine or analogue may be of one or both of two types. Firstly, a condensation reaction may take place with the elimination of the hydrogen atom from the thiol or analogous group in the dialkylcysteine or analogue and an anion bonded to the metal in the metallic compound, a direct covalent linkage being established between the metal radical and the sulphur, selenium or tellurium atom in the dialkylcysteine or analogue. At the same time a coordinate bond is formed between the nitrogen atom in the latter compound and the metal atom. Secondly, and alternatively or additionally, a wholly coordinate linkage may be established between the metal atom and the sulphur, selenium or tellurium atom and the nitrogen atom in a dialkylcysteine or analogous molecule.

The derivatives may be prepared by mixing an appropriate metal oxide or halide, or a hydrohalide of an appropriate organo metallic compound, suspended or dissolved in water, alcohol, glycerol or other suitable polar solvent with the selected dialkylcysteine or dialkylcysteine analogue. Condensation compounds formed may be separated if desired by adding ether, acetone or other organic liquid in which the product is insoluble.

A variation of this method consists in dissolving in alkaline solution stoichiometric amounts of a metallic salt and the dialkylcysteine or dialkylcysteine analogue, and then if desired isolating the reaction product with ether or the like, as above.

An alternative method consists in the electrolysis of an inorganic salt of the desired metal dissolved in a solution containing water along with the dialkylcysteine or dialkylcysteine analogue: the metal ions will enter into a condensation reaction with the dialkylcysteine or dialkylcysteine analogue, the product then being isolated if desired. Both racemic and dextro rotary dialkylcysteines may be used for the synthesis, the dextro forms providing compounds of greater therapeutic index.

The invention is particularly applicable to compounds of arsenic, antimony, and bismuth containing an organic group or groups. Preferably, the ratio of the metallic compound to the dialkylcysteine ligand is adjusted to provide the greatest increase in therapeutic index. The resulting compound or complex may be utilized in the form of mixtures, solutions, and/or products obtained by the precipitation of solutions of the constituent compounds.

The unexpected therapeutic efficiency of the products of the invention is illustrated by the following experimentally obtained information. A lethal dose (LD_{50}) of 3-amino 4-hydroxyphenylarsenoxide (arsenoxide) reacted according to the invention with the same amount of dimethylcysteine is completely detoxified (in each case 50 mg./kg. given subcutaneously to mice). On the other hand, the therapeutic activity of the minimal effective dose of arsenoxide which induces disappearance of the parasites from the blood stream of mice infected with trypanosomes (*T. equiperdum*), namely 1-3 mg./kg. maintains its effectiveness when used after reaction with the same quantity of dimethylcysteine, and even with such excess quantities as 100-200 mg./kg. dimethylcysteine. It is characteristic of the specificity of this observation that under similar conditions, other thiol antidotes of arsenic poisoning, as BAL, act in the opposite manner; that is to say they abolish more promptly the therapeutic than the toxic action of arsenoxide; to detoxify Mapharsan (arsenoxide), 1.0-2.7 times more BAL than Mapharsan is required, while the curative effect disappears with doses of BAL as small as $\frac{1}{6}$ to $\frac{1}{2}$ of the Mapharsan weight (Ercoli and Wilson. *Jour. Pharmacol. and Experim. Therapeutic* 92: 121-126. 1948). Therefore, mixtures of BAL or BAL glycoside with arsenicals or antimonials are not therapeutically useful.

Thus the dimethylcysteine or ethyl-methyl-cysteine sub-

stitution of the oxygen or chlorine atoms of aromatic arsenoxides or dichlorarsines (Aryl-AsO; Aryl-AsCl₂) increases their therapeutic index by decreasing their toxicity, while maintaining or improving the effectiveness of known effective preparations. Other therapeutically insignificant substituted aryl compounds assume useful properties by the introduction of this new —As=R₂ radical (where R is a dialkylcysteine radical).

This substitution is particularly advantageous for 3-acetamino-4-hydroxy-arsinoxide to obtain a product of low toxicity for the treatment of amoebiasis and for -arsenobenzamide to obtain an antifilarial drug with better therapeutic index.

Analogously to the arsenicals, I have discovered that dimethyl or β -ethyl- β -methylcysteine detoxifies organic antimony preparations (e.g. antimony alkali tartrates, antimony gluconate) when reacted therewith without interfering with their therapeutic efficiency. A similar effect was noted when using the N-acetyl derivatives of these dialkylcysteines, though to a lower degree.

In contrast, it is known (Chen et al. *Jour. Infections Diseases*. 76: 152-154. 1945) that cysteine itself reduces toxicity to the same extent as the antiparasitic effect of the antimonials. Thus, its positive antidotal action becomes counterbalanced by its negative effect on therapeutic efficiency and the combined treatment is not practicable. Similar results were obtained with a number of other antidotes of metal poisoning containing —SH and —NH—groups (benzoylarnino- β , β -dimethyl acrylic thiol acid and α -benzoylarnino- β -mercapto isovaleric thiol acid) structurally close to the dialkylcysteines (Ercoli et al. *Archiv. Internat. Pharmacodyn.* 136: 452-462. 1962). In the studies conducted in connection with the present application, it has been established that the antiparasitic action of 10 mg./kg. antimony potassium tartrate (against *Trypanosoma equiperdum*) is destroyed by 0.7 mole, or less, of sodium dimercaptosuccinate, while 35 moles or more of d. or dl. dimethylcysteine did not affect it. Dimethylcysteine acetonide proved ineffective in changing the therapeutic index. The specificity of this invention for the specified dialkylcysteines is further confirmed as far as antihelmintic action is concerned by the reports (O. D. Stander in *Experimental Chemotherapy*. I. Schnitzer and Hawking. Academic Press, New York, London, 1963) that antimony tartrate is detoxified as much as deactivated by dimercaptosuccinate and other dithiols.

The high toxicity of selenium, which given as selenite in microgram doses prevents liver necrosis and bound to certain organic radicals is cytostatic, is reduced when it takes the place of sulphur in the above formula. In this form, the Me-Se linkage induces a "reverse detoxification," namely the relatively much more toxic Se (or Te) is detoxified by the metal binding and can be used as cytostatic or antinecrotic agent.

The derivatives of the invention are illustrated by the accompanying examples:

Example 1

One part of potassium antimony tartrate (tartar emetic) is mixed with 1.5 or 2 parts of dl. dimethylcysteine or d. dimethylcysteine hydrochloride in powder form, and is heat sterilized and vailed as dry powder, which is stable over a period of years. The product obtained is soluble up to 6.15% in bidistilled water; the 5-6% solution indicated for treatment has a pH of ca. 6.4.

Besides the decrease of the general toxic effect of the antimony radical in this preparation, the local necrotizing effect of the tartar emetic disappeared also, in such a manner that the product can be injected intramuscularly (while tartar emetic can be given intravenously only), with the obvious advantages of this property for mass therapy. The therapeutic, and biological properties of two preparations containing 1 part of tartar emetic and

respectively 1.5 parts (referred to as TP15) and 2 parts (referred to as TP2) of dl. dimethylcysteine are illustrated in Table 1.

and molecular weight 440.04, together with 0.8 part excess dimethylcysteine, corresponding to a 2.4 fold molar excess of the dimethylcysteine, which forms a complex

TABLE I

Preparation	Toxicity in mg./kg. Sb				Therapeutic dose in trypanosomiasis Sb, mg./kg.				Schistosomicidal dose Sb, mg./kg.	Therapeutic index in Schistosomiasis
	LD ₅₀ mouse subcut.	Rabbit tolerated intrav.	Dog	Irritating action	Clarifying	Curative	Clarifying	Curative		
K-antimonyltartrate (tartar emetic).	18	3.6	5.75 ¹	High, 0.1%----	2.65	11	6.7	1.7	7.3	1.8
Fuadin-----	110	-----	None, 5%----	4.1	20.4	27	5.3	41	2.7	
TP15-----	51	8.6 (tox.)	None, 6%----	1.8	10.1	28	4	7.5	6.8	
TP2-----	83.5	8.4	28 i.m. ¹	None, 6%----	1.8	10.1	46.5	7.8	8.8	9.5

¹In daily doses of 1.2-2.8 mg./kg.

While there is an optimum proportion between the metal-organic compound and the dialkylcysteine to obtain the highest therapeutic index, these proportions may be varied over a broader range as illustrated by FIG. 1 (in the case of tartar emetic and dl. dimethylcysteine the optimal ratio is 1:4 molar). Among other changes in biological properties, the direct antiparasitic activity of the antimonial has been also increased to a considerable extent in the solution with the dialkyl cysteine. Cercariae of the *Schistosoma mansoni* exposed to tartar emetic were immobilized within 3 hours when exposed to 10⁻⁶ moles in the solution containing 2 parts dl. dimethylcysteine (TP2 of Table 1), while alone a much higher concentration (1/70,000 mole) of emetic gave this effect only after 5 hours. Similarly, the tripanocidal activity has been increased 2 to 3 fold taking as criterion of comparison both the immobilization and destruction of the parasites. (This potentiating effect is due presumably to a greater penetration of the parasite of the product formed in the solution with dialkylcysteines.) An identical procedure for preparation can be used, replacing antimonyl tartrate with sodium antimonyl glyconate (Tristam).

Example 2

One part of sodium antimonyl tartrate is mixed with 1.66 parts of dl. dimethylcysteine and is heat sterilized and vialled as dry powder, as in Example 1. The resulting complex-compound, containing 14.9% Sb, had an LD₅₀, given subcutaneously to mice, corresponding to 82-110 mg./kg. Sb, in comparison to 8-10 mg./kg. Sb for the sodium antimonyl tartrate used for its preparation. Thus, the degree of detoxification is considerably higher than in the previous example (TP15 and TP2), reaching a toxicity decrease in the order of 1:10. This highly detoxified complex compound has been used clinically, under the name of NaP, for intensive treatment (short term therapy over 5-8 days) of bilharzia patients. The patients received one intramuscular injection for five consecutive days of 400 mg. NaP injected intramuscularly in 5 ml. bidistilled water. The injections were painless and well tolerated. The curative results obtained were the highest reached so far in the treatment of this disease, 87% clearing rate of bilharzia patients observed for a period of 3-6 months for egg elimination. The comparative results with other drugs obtained in the same Bilharzia Service Centre as far as tolerance and therapeutic effect are contained in Table II.

This preparation (NaP) given orally to man in enterocoated pills or capsules was well tolerated in daily doses corresponding to about 100 mg. Sb, the highest tested so far.

The preparation (NaP) comprises the compound sodium antimonyl-dimethylcysteinyl tartrate having the probable structure.

with the compound by means of coordinate bonds with the Sb atom.

Clinical activity of the new antimonial complex compounds NAP (Example 2) and TP2 (Example 1) in comparison to other modern antimonials.

Data collected by the "Centro De Lucha Antibilharziana," Ministerio De Sanidad Y Asistencia Social, Venezuela, Caracas, under the direction of Dr. Miguel Ron Pedrique.

TP2 (200 mg. Sb total)-----	51	± ²	
NAP (298 mg. Sb total)-----	87	± ²	

¹Cases of lethal toxicity.

²Almost nil.

The statistics on TP2 and NaP are based on 220 Bilharzia cases, while the other data on Fuadin and Anthiomalin are the result of about 20 years of experience of the Centre on thousands of patients. Astiban has been tested by Dr. Ron Pedrique and coworkers on 95 cases.

Example 3

One gram of K-antimonyl tartrate and 1.5 grams of dl. dimethylcysteine are dissolved in 40 cc. distilled water 40°. The addition of 300 cc. of acetone or 400 cc. ethyl-alcohol forms a crystalline deposit with an Sb content of 14-15%, and a LD₅₀ corresponding to 40-50 mg./kg. Sb injected subcutaneously in mice (ca. 3 times that of antimonyl tartrate) with a curative index in trypanosomiasis 100-150% higher than that of the Sb tartrate used for the preparation.

The Sb content of the crystalline preparations so obtained can be varied according to the ratio of antimonial and dialkylcysteine used, all having an increased therapeutic index in relation toxicity referred to Sb content. The optimal preparations for therapeutic use are those containing 10 to 20% Sb, obtained by the method described from the original organic compounds containing 36 to 39.5% Sb (antimony potassium tartrate 36.5% : antimony sodium tartrate 39.4% : sodium antimonyl gluconate 36%). These materials are suitable for the preparation, purification and isolation of chemical compounds of defined structural formula containing Sb and two organic radicals, one of them the dialkylcysteine, the other respectively tartaric or gluconic acid for example.

Example 4

(a) One gram of 3-amino-4-hydroxyphenylarsenoxide (arsenoxide) was uniformly mixed with 2 grams of d. dimethylcysteine hydrochloride, 3.0 grams sucrose, 0.18 gram sodium carbonate and 0.03 gram ascorbic acid. The preparation was vialled to contain 60 mg. arsenoxide for single adult dose (162 mg. of the mixture), dissolved in distilled water before use. The LD₅₀ for mice of the arsenoxide-dimethylcysteine derivative in the prepara-

75

tion was 150 mg./kg.: i.e. the preparation decreased 2.7 fold in toxicity with an activity identical to the starting product, which represents a corresponding (2.7×) increase in safety. Improvement of the safety factor, to varying degrees, is obtained using 1 part arsenoxide and 0.5 to 6 parts of d. dimethylcysteine hydrochloride.

The lower toxicity of the product extends not only to the systemic but even to the local action of the arsenical, which in the form of the present composition can be utilized by intramuscular injection also. While arsenoxide caused severe necrotic lesions on rabbit skin in 1-2 mg./ml. concentrations (given intradermally), 20 mg./ml. of the arsenical in presence of the dialkylcysteine induced no lesions.

The intramuscular use of arsenoxide practicable in the form of the preparations here described permits the combined treatment with other drugs in the form of a single pharmaceutical preparation, without having to resort to two different routes of administration (e.g. intravenous for arsenoxide and intramuscular for penicillin).

(b) Similar improved therapeutic products can be obtained using 1 part of 3-amino-4-hydroxyphenyldichlorarsine hydrochloride (dichlorphenarsine) with 2 parts of dl. dimethylcysteine. The subcutaneous tolerated dose of dichlorphenarsine increased from 12 mg./kg. As to over 32 mg./kg. As (Table 3), while the trypanocidal activity in vivo remained unaltered and in vitro became even higher: 0.09 μ g./ml. As in the form of dimethylcysteine preparation in comparison to 0.14 μ g./ml. As of dichlorarsine.

The therapeutic properties of the product can be accounted by the formation in solution of 3-amino-4-hydroxyphenarsine-di- β , β -dimethylcysteine. This compound has a tolerated dose corresponding to 18 mg./kg. As, but it has been further detoxified to 35 mg./kg. As (Table B) by the presence of excess dl. dimethylcysteine which through coordination bonds with the As atom forms a complex of the new compound.

TABLE III

Toxicity of dichlorphenarsine alone and with dl. dimethylcysteine compared with trichlorhydrate of 3-amino-4-hydroxyphenarsine-di- β , β -dimethylcysteine

Preparation	As content, percent	Total dose drug, mg./kg. subcutan.	No. mice injected	No. mice died
Dichlorphenarsine-----	25.8	50	12	0
1 part Dichlorphenarsine plus 1 part dl. dimethylcysteine-----	12.9	75	9	7
1 part Dichlorphenarsine plus 2 parts dl. dimethylcysteine-----	8.65	100	8	8
3-amino-4-hydroxy phenarsine-di- β , β -dimethylcysteine.3HCl-----	12.08	150	6	0
		250	6	0
		300	3	3
		300	3	0
		600	3	3
		800	3	3
		150	4	2
		200	4	4
		300	4	0

(c) Trichlorhydrate of 3-amino-4-hydroxy-phenarsine-di- β , β -dimethylcysteine (or 3-amino-4-hydroxy-phenylarsonide-DL- β -mercapto-valine). 2.2 grams DL-dimethylcysteine contained in 9 ml. ethanol were slowly added to 2 grams of 3-amino-4-hydroxy-phenyldichlorarsine hydrochloride dissolved in 6 ml. ethanol. The mixture was heated by refluxing for 1 hour, the material remaining insoluble being removed by vacuum filtration. To the filtrate first 10 ml. ethanol then 50 ml. chloroform were added, which induced the formation of a white precipitate. This was filtered, and desiccated in vacuo where it lost its resinous consistency and became a white-grayish powder. Dried to constant weight at 40° C. in vacuo it lost 4.4% weight. The analysis gave values corresponding to the formula:

containing (calculated) As, 12.7%; C, 32.2%; N, 7.1%; S, 10.7%; H, 4.95%; O, 13.6%; Cl, 18%. I found: As, 12.08%; C, 29.75%; N, 6.6%; SIO, 2%; H, 4.54%; O, 15.2%; Cl, 21.65%;

The minimal lethal dose of this compound for mice is 200 mg./kg., while it clarifies *Trypanosoma equiperdum* infection of the same species in 2.5-3.0 mg./kg. subcutaneous doses and induces permanent cure with 12 mg./kg. Compared to the corresponding arsenoso (-AsO) compound, Arsenoxide (Mapharside), the therapeutic index has been increased by not less than 100%. The improvement of the therapeutic index is even greater with the dextrorotatory compound.

Example 5

Similar increases in therapeutic indices occur using as starting material for the preparation 4-carbamyl-phenyl-dichlorarsine to obtain p-arsenosobenzamide-dialkylcysteines or 3-acetamino-4-hydroxy-phenyldichlorarsine and p-ureido-phenyldichlorarsine for condensation with the dialkylcysteine. As in the case of the antimonials, the dextro form of the selected dialkylcysteine will result in the less toxic compound, with a higher therapeutic index.

Example 6

Arsenamide (4-carbamido phenyldicarboxy methylthio-arsenite) is "an efficient antifilarial drug, but it is too toxic for general use" (Brit. Med. Dictionary. Sir. Arthur Salisbury, Caxton Publishing Comp. London. 1961).

Efficient products of reduced toxicity are prepared (a) by dissolving 1-3 parts methyl-ethylcysteine or dimethylcysteine powder kept in sterile vials in a commercial solution of arsenamide just before use. A vial containing 160 mg. dl. dimethylcysteine is suitable for dissolution in 6-8 cc. 1% arsenamide at pH 7: by an alternative method consisting in the preparation of dry mixtures of the sodium salt of arsenamide, 80 mg. per vial with 150 mg. of dl. dimethylcysteine to be dissolved before injection.

Example 7

One part of N-carbamylarsanilic acid (Carbarsone) is

mixed with 0.2 part calcium gluconate and 0.7 part of dl. dimethylcysteine. The composition is used in the form of capsules (500 mg.) for the treatment of amebiasis.

Example 8

One part of sodium bismuth thioglycollate (Thiobis-mol) is mixed with 0.75 part of d. dimethylcysteine. The product is administered in capsules of 400 mg. (in *Vicent angina*) and intramuscularly. It may be kept in vials, in doses of 400-600 mg. The therapy can be supplemented with a higher calcium intake.

Example 9

(a) One part of antimony trichloride is mixed with 2.4 parts dl. dimethylcysteine and 2 parts of sodium carbonate under careful conditions of dryness. The resulting snowy powder dissolves rapidly in water with libera-

tion of CO_2 . The 5% solution of the mixture has a pH of 6.8 and can be injected without causing lesions. Its LD_{50} for mice (subcutaneous) corresponds to slightly over 100 mg./kg. Sb (Table 4).

The reaction which takes place by dissolving the mixture in water leads to the formation antimony-tris-dl- β,β -dimethylcysteine which has a lethal dose corresponding to 30 mg./kg. Sb, but can be considerably increased by the addition of 25-50% excess dl. dimethylcysteine (Table 4).

In the mixture of the present example the theoretical ratio for the reaction between SbCl_3 and dimethylcysteine is 1.9, while an excess of 2.4 parts dialkylcysteine was used, which accounts for the high tolerance of the new product, since a complex is formed in the solution with the excess dimethylcysteine.

In this example it has been established that a compound is formed which is further detoxified by the excess dl. dimethylcysteine entering into a complex with the new compound formed in solution. The new compound-complex is antimony-tris-dl- β,β -dimethylcysteine, with its Sb bound by coordinate linkages to the excess dl. dimethylcysteine.

Increase of the proportion of dimethylcysteine in the mixture with antimony-tris-dl-dimethylcysteine did not produce further detoxification (in fact, it reduced it), proving that the resulting toxicity and biological characteristic of the mixture in aqueous solution is determined by the equilibrium between the new chemical structure and the ligand dl. dimethylcysteine. Toxicity of antimony-tris-dl- β,β -dimethylcysteine ($\text{Sb}(\text{DMC})_3$) and its DL-Dimethylcysteine complexes, compared to preparation of (Example 9a).

white crystals melting with decomposition at 165-170° C. were obtained. Analysis gave values corresponding to a monohydrochloride of the expected compound: $\text{SbC}_{15}\text{H}_{30}\text{N}_3\text{O}_6\text{S}_3\text{HCl}$ (M.W. 602.26). Theoretical values: Sb, 20.2%; C, 29.9%; H, 5.15%; N, 6.9%; O, 15.9%; S, 15.9%; Cl, 5.9%. The experimental values found were: Sb, 19.5%; C, 31.68% (in other samples 29.43% and 30.17%); H, 4.71% (4.91% and 5.01%); N, 6.37%; O, 17.25%; S, 15.30% (15.9% and 15.62%); Cl, 5.48%.

In two of the three preparations analyzed, prepared with various modifications of the above method (reflux heating instead of autoclaving), the Cl values were lower (2.95% and 2.5%), which was due to more prolonged washing of the "wet trioxide" leaving insufficient HCl to bind the whole of the free amine in the form of hydrochloride.

The lethal dose (LD_{50}) of the compound administered subcutaneously to mice was 150 mg./kg., while the dose clearing a *Trypanosoma equiperdum* infection was 10 mg./kg., i.e. $\frac{1}{15}$ of the lethal dose. The toxicity of the compound could be further decreased, to a LD_{50} of 400 mg./kg., while the therapeutic effect was fully maintained, by adding 0.25 parts dimethylcysteine to one part of the compound, corresponding to a one molar excess of dimethylcysteine, the compound forming a complex with this excess.

The products containing an excess of dialkylcysteine are particularly suitable for oral administration, by counteracting the tendency of the organic derivatives and of the chelates to decompose at the low pH of the gastric content. The treatment with antimonials tolerated and absorbed by the oral route, besides its obvious advantages

TABLE IV

Preparation	Sb content, percent	Total dose drug, mg./kg. subcutan.	No. mice injected	No. died
$\text{Sb}(\text{DMC})_3$	19.5	100 150 200	3 3 4	1 1 4

1st sample: SbCl_3 /dimethylcysteine, ratio 2.4....	15.5	300 600 800 200 400	2 2 5 2 2	0 0 4 0 0
2nd sample: SbCl_3 /dimethylcysteine, ratio 2.7....	14.6	600 800 1,000	3 3 8	0 3 7
Pretreatment with 200 mg./kg. dimethylcysteine subcutaneous followed by $\text{Sb}(\text{DMC})_3$		400	4	0

Note.— $\text{Sb}(\text{DMC})_3$ itself is protected against its lethal effect by pretreatment with dimethylcysteine, without losing therapeutic effectiveness.

(b) Analogous preparations can be obtained with a mixture of antimony oxide and dialkylcysteines, however, these enter more slowly into solution and generally require heating.

(c) Twenty grams of SbCl_3 were added to 100 ml. water to form a mass of 16 grams of "wet trioxide" (a mixture of Sb_2O_3 and hydrochloric acid). This mass was rapidly washed on a filter (with ca. 20 ml. water) then added to 100 ml. distilled water in which 10 grams DL-dimethylcysteine were dissolved. The mixture was heated in an autoclave at 120° F. and 15 lbs. pressure for 2 hours, refiltered and the filtrate concentrated in vacuum to encourage the formation of crystals which were pH. This preparation (the free amine) has the same bio-formed in a heavy mass on the addition of alcohol. By successive recrystallization from water-alcohol mixtures,

for mass therapy, leads also to relatively higher Sb concentrations in the portal system where the schistosomes are localised in a *S. mansoni* infection.

(d) 9.34 grams DL dimethylcysteine were dissolved in 100 ml. water in a 3-necked 500 ml. round bottomed flask and stirred, while N_2 gas was passed into the flask to minimise air oxidation. After 4.98 gm. NaOH had been added, 4.75 g. SbCl_3 dissolved in 25 ml. absolute alcohol were added slowly from a dropping funnel; a precipitate appeared briefly, but immediately redissolved. Stirring was continued for 30 minutes and then the solution was refluxed on the water bath for 1 hour. To the reaction mixture, concentrated in a flash evaporator to a small volume, dry alcohol was added. The precipitate was filtered, washed with alcohol and dried under vacuum. The product, a white solid, was readily soluble in water at neutral

logical characteristics as the mono-hydrochloride. In doses of 200 mg./kg. it killed 75% of the mice to which it was administered (i.e. its LD₇₅ was 200 mg./kg.), while 12.5 mg./kg. cleared *Trypanosoma equiperdum* from all infected animals treated.

Example 10.—Antimony-D-dimethylcysteine hydrochloride

(a) The reduced toxicity of the product of mixing antimony trioxide with d.dimethylcysteine hydrochloride was found to be due to the formation of antimony-d-dimethylcysteine-hydrochloride. The tolerance of this compound was the highest encountered, corresponding to an LD₅₀ (mouse) of 245 mg./kg. Sb, with a favourable therapeutic index in trypanosomiasis, infected mice being cleared by $\frac{1}{40}$ of the lethal dose, i.e., 25 mg./kg. of the preparation, corresponding to 6.2 mg./kg. Sb.

(b) One gram of d-dimethylcysteine hydrochloride was dissolved in 10 ml. distilled water, and to this solution 1 gram of freshly precipitated (from SbCl₃), wet Sb₂O₃ is added. The suspension was refluxed over a water bath for 3 hours. After filtration, it was concentrated by vacuum-centrifugation leaving an oily material; this was dissolved in ethyl alcohol and precipitated with ether. The white powder melted with decomposition at 168-170° C. Microanalysis gave values corresponding to the formula

Found: C, 23%; Sb, 24.4%; H, 3.7%; N, 5.8%; O, 12.9%; S, 12.9%; Cl, 12.4%. Calculated: C, 24.5%; Sb, 24.7%; H, 4.4%; N, 5.7%; O, 13.0%; S, 13.0%; Cl, 14.6%.

Example 11.—Mercury-d-dimethylcysteine hydrochloride

Two grams of HgCl₂ were dissolved in 100 ml. distilled water and 16 ml. NaOH solution added. The insoluble HgO precipitated was repeatedly washed with distilled water on a filter, then resuspended in 15 ml. distilled water. This suspension was slowly added to 60 ml. of a solution containing 1.5 grams d-dimethylcysteine hydrochloride heated at 70° C.; the mercury oxide immediately dissolved. The reaction product can be recrystallised by gradual cooling or recovered quantitatively by the addition of 2-3 volumes of a mixture of butyl alcohol and ether, or by adding ethyl alcohol. The white product precipitated by alcohol decomposed at 177-185° C., that precipitated by the butylalcohol-ether mixture at 180-190° C., giving a peculiar characteristic odor which accompanies the decomposition of these metal-organic compounds, and a black residue of HgS.

Example 12.—Mercury -dl- dimethylcysteine hydrochloride

2.01 grams of HgCl₂ were dissolved in 30 ml. absolute alcohol and 2.3 grams of DL. dimethylcysteine were suspended in 105 ml. of the same medium in an Erlenmeyer flask. The HgCl₂ solution was heated on water bath while the alcoholic dimethylcysteine suspension was slowly added to it. The suspension went immediately into solution as a result of the reaction with the HgCl₂. The reaction product could be collected by slow crystallization after cooling or by precipitation with ether. The white crystals formed, observed on a heated plate under the microscope, started to volatilize at 170° C. without melting; before the temperature reached 180° C. a black residue was formed. The compound was water soluble; on heating the solution became turbid, but the addition of NaOH clarified it. HgS was precipitated by the addition of H₂S in acid solution. Its formula was Hg(SC₅H₁₀O₂N.HCl)₂ (Hg, 35.2%; H, 3.85%; C, 21.2%; S, 11.3%; Cl, 12.4%). Microanalysis gave the following

experimental values: Hg, 38.75%; H, 4.17%; C, 22.26%; S, 11.18%; Cl, 12.45%. The material, alone or in combination with dialkylcysteine, can be used as an anti-bacterial and/or diuretic agent.

5 Example 13.—Ferrous and ferric d- and dl. dimethylcysteine

(a) 1 gram ferric sulphate was dissolved by heating in 200 ml. water and ferric oxide precipitated with 10 ml. 5% NH₄.OH. The ferric oxide formed was washed until neutral on the filter, then suspended in 60 ml. water. To this suspension 600 mg. of DL-dimethylcysteine hydrochloride (or the free amine) dissolved in 45 ml. water were added. The mixture on being heated to boiling for 10 minutes took on a dark violet colour; it was filtered and 100 ml. ethanol and 200 ml. ether were added to the filtrate. Two layers formed, the superior colourless, the inferior violet and containing the compound, and were separated. To the violet liquid 80 ml. alcohol and 200 ml. ether were added, which induced the precipitation of the expected compound: Fe(C₅H₁₀NO₂S)₃ which had a brownish colour, was soluble in alkalis, and on neutralization was precipitated by H₂S. It had a strong tendency to hydrolyze and to reform the insoluble Fe oxide.

(b) 500 mg. FeSO₄.7H₂O (M.W. 278.03) were dissolved in 5 ml. glycerol and 550 mg. DL. dimethylcysteine (M.W. 151.18) in 15 ml. glycerol. A current of hydrogen was passed through the solutions before mixing them, whereupon the combined solution was saturated with NH₃ until the initially violet colour turned to yellowish. From 20 this solution, by adding a mixture of two volumes alcohol and 408 volumes ether, an oily yellow deposit was first obtained which by successive treatment gave a solid material comprising mainly the reaction product 25 expected: Fe(C₅H₁₀NO₂S)₂. This product was water and alkali-soluble and was easily decomposed to give the insoluble oxide.

(c) On electrolysis in a U-tube of 100 mg. FeSO₄.7H₂O and 120 mg. DL. dimethylcysteine in 13 ml. glycerol to 30 which 1 ml. water was added, at 0.5 ma. and 200 volts, the solution on the cathodic side became an intense violet colour. The violet solution collected from the cathodic side of the U-tube, precipitated with 2 volumes of alcohol and 5 of the ethyl-ether gave a bluish product, a mixture of the ferric and ferrous dimethylcysteine derivatives. This preparation was easily decomposed into the brownish oxide. (With proper precautions, maintaining a tight hydrogen chamber on this cathodic side of the tube it is possible to avoid the oxidation of the ferrous form.)

(d) Using dialkylcysteines soluble in organic solvents, 35 for example D-dimethylcysteine hydrochloride, which is soluble in ethanol, a practical method of preparation consists in placing the dialkylcysteine over a layer of the same weight of ferric hydroxide, freshly prepared as in Example 5a, but washed with alcohol after precipitation, in the extractor chamber of a Soxhlet apparatus. The alcohol vapour condensed in the chamber dissolves the dialkylcysteine and passing through the oxide, forms the reaction product, which drops continuously into the bottle generating the alcohol vapour. Under these conditions, a brownish product, soluble in water, is formed, which on heating decomposes leaving a black residue (FeS). Both the ferrous and ferric dialkylcysteine derivatives can be used as hematopoietic agents.

60 Selenium and tellurium derivatives of dialkylcysteines 65 may be prepared by similar methods. It is believed that they may be effective as cytotoxic agents to inhibit excess cell growth.

Example 14

Further examples of dialkylcysteine derivatives of metal-70 lo-organic compounds are given below: Diphenylethyl-methyl-chlorarsine

75 reacting with the dialkylcysteine gives an arylalkyl

(alkyl)(mono - dialkylcysteine)arsine. The arylstibonous halides ($ArSbCl_2$) or the aroxostibines ($NH_2C_6H_4-SbO$) form di-dialkylcysteine compounds. Chlorodiphenylstibine ($(C_6H_5)_2SbCl$) forms a diaryl(mono)dialkylcysteine-stibine. Correspondingly, 2,chloro-1,3 dithia-2-arsacyclopentane.

forms a 2 - dialkylcysteinyl-1,3-dithia-2-arsacyclopentane, as does the stibiacyclopentane derivative of dimercaptopropanol (BAL) in which 2 bonds of 3-valent Sb are linked in an internal dithiol ring, the third to the dialkylcysteine selected. Other heterocyclic organo-metallic compounds containing for example arsindole, 1,3-dithia-arsacyclopentane, 1,3-stibiacyclopentane, phenothiarsine, or dimercaptopropanol-cyclic-bismuth rings may also be used. Triphenylbismuth dichloride ($(C_6H_5)_3BiCl_2$), gives a triaryl-bis (dialkylcysteine)Bi compound.

What is claimed is:

1. Alkali metal salts of antimony-dialkyl cysteinyl tartaric acids and complexes thereof with dialkyl cysteines.
2. Products of the reaction in aqueous solution of 4-carbamide phenyldicarboxy methyl thioarsenite with a dialkyl cysteine.
3. Products of the interaction in aqueous solution of N-carbamylarsanilic acid and an dialkyl cysteine.
4. Products of the interaction in aqueous solution of sodium bismuth thioglycollate and a dialkyl cysteine.
5. 2-dialkyl cysteine-1,3-dithia-2-arsacyclopentane.
6. 2 - dialkyl cysteine - 1,3 - dithia - 4 - methylol - 2 - stibiacyclopentane.
7. Triaryl-bis-dialkyl cysteine-bismuth.
8. 2-dialkyl cysteine-1,3-dithia-4-methylol-2-bismuthyl-cyclopentane.

9. Alkali metal salts of antimonydialkyl cysteinyl gluconic acid, and complexes thereof with dialkyl cysteines.
10. 4-carbamyl phenarsine-di- β,β -dialkylcysteine.
11. 3-acetamino-4-hydroxy phenarsine-di- β,β -dialkylcysteine.
